G. G. OVERN & J. C. THORESON.
DEVICE FOR DETACHABLY SUPPORTING WATER CONDUCTORS.
APPLICATION FILED JUNE 23, 1914.

1,126,845.

Patented Feb. 2, 1915.

UNITED STATES PATENT OFFICE.

GUSTAV G. OVERN AND JOHN C. THORESON, OF KATHRYN, NORTH DAKOTA.

DEVICE FOR DETACHABLY SUPPORTING WATER-CONDUCTORS.

1,126,845.

Specification of Letters Patent.

Patented Feb. 2, 1915.

Application filed June 23, 1914. Serial No. 846,868.

To all whom it may concern:

Be it known that we, GUSTAV G. OVERN and JOHN C. THORESON, citizens of the United States, residing at Kathryn, in the 5 county of Barnes and State of North Dakota, have invented certain new and useful Improvements in Devices for Detachably Supporting Water-Conductors, of which the following is a specification.

- 10 This invention relates to an improved device for detachably supporting water conductors in operative position, and has as its primary object to provide a construction which may be readily attached to a building or other object to which it is desired to connect the conductor, and which is adapted to be readily engaged with or disengaged from the conductor after being secured in position to receive the conductor.
- 20 The invention has as a further object to provide a device of this character so constructed that the portion thereof arranged to engage the conductor may be brought into severe frictional contact with the wall 25 thereof to thus effectually support the conductor in position, and wherein the means employed for locking the device upon the conductor may effect such frictional engagement upon its application to operative 30 position.

A still further object of the invention is to provide a support of the above described character wherein a detachable reinforcing strip is employed and arranged to embrace 35 the support at the point of its connection with the building or other object to which the support is attached, to the end, that the support may be rigidly and securely held in position.

- 40 With these and other objects in view, our invention will be more fully described, illustrated in the accompanying drawings, and then specifically pointed out in the claims which are attached to and form a part of 45 this application.

In the accompanying drawings:—Figure 1 is a perspective view, showing our improved support applied in operative position, Fig. 2 is a detail perspective view of 50 the support showing the locking plate detached therefrom, but in proper relative position, Fig. 3 is a horizontal sectional view particularly showing the disposition

of the reinforcing strip, and Fig. 4 is a detail perspective view of the reinforcing 55 strip.

Corresponding and like parts are referred to in the following description and indicated in all the views of the drawings by the same reference characters.

Referring more particularly to the drawings, we have illustrated in Fig. 1 thereof our improved support applied in operative position, and wherein the numeral 10 designates a water conductor or down-spout, 60 which may be formed of suitable sheet metal, the wall thereof being bent upon its longitudinal edges to provide the interlocking joint 11, and, if desired, being corrugated longitudinally, as shown.

Coming now more particularly to the subject of the present invention, our improved support includes the body portion 12, substantially of the form of a split ring, and which is preferably constructed of suitable 75 sheet metal. Adjacent its extremities, the body portion 12 is turned outwardly to provide laterally disposed hooks or flanges 13 which are arranged obliquely to the vertical plane of the body portion 12, the said 80 hooks being each inclined to converge toward each other adjacent one extremity thereof, and toward one side edge of the body portion 12.

Detachably mounted upon the body portion 12 midway the ends thereof is a reinforcing strip 14. This strip is also preferably formed of suitable sheet metal and is arranged to embrace the body portion 12, the body portion 15 of the reinforcing strip 90 being preferably arranged to extend transversely of the body portion 12 of the support upon the inner face thereof and being bent adjacent its extremities to provide the laterally disposed confronting hooks or 95 flanges 16, the flanges 16 being arranged to embrace the opposite side edges of the body portion 12 to bear at their extremities against the rear face of said body portion.

Medially formed in the body portion 16 100 of the reinforcing strip is a suitable aperture 17, which is disposed to coincide with a similar aperture formed in the body portion 12 of the support, the said aperture being designed to receive a screw 18 or other 105 fastening means by which the device may be

attached to the building or other object upon which it is desired to support the conductor. From the above description and upon particular reference to Fig. 2 of the drawings, it will be noted that when the body portion 12 of the support is thus arranged upon a building or other object, that the conductor 10 may be readily inserted therein to be secured in operative position, and particular attention is directed to the fact that the reinforcing strip 14 not only serves to strengthen the joint between the screw 18 and the body portion 12 of the support, but provides a relatively large bearing surface arranged to absorb the strain upon the body portion 12 at the point of its connection with the screw 18, due to downward pull exerted by the weight of the conductor 10.

20 Detachably connecting the extremities of the body portion 12 of the support together is a locking member 19 which is also preferably formed of suitable sheet metal and which is bent laterally adjacent its longitudinal edges to provide the inwardly turned flanges 20, which are each obliquely arranged to converge toward each other adjacent one extremity and toward one side edge of the locking member. By this construction, it will be observed that the oppositely inclined flanges 20 of the locking member 19 are disposed to engage the similarly inclined flanges 13 of the body portion 12 of the support, as best shown in Figs. 1 and 2 of the drawings, and it will be noted that as the locking member 19 is moved to position upon the body portion 12 that the extremities thereof, will be drawn together to be brought into severe frictional engagement with the wall of the conductor 10. It will thus be seen that the conductor 10 may be readily positioned within or removed from the support by attaching or detaching the locking member 19, and at this point, it is desired 45 to bring further and particular attention to an additional function of the reinforcing strip 14, in its relation to the conductor 10. As best shown in Fig. 3 of the drawings, when the conductor 10 is arranged in operative position within the support, the body portion 15 of the reinforcing strip 14 is preferably disposed within one of the furrows formed by the corrugations in said conductor to contact at its side edges against 50 the contiguous oppositely inclined walls of the corrugations formed by the adjacent ridges of the corrugations. The said side edges of the body portion 14 of the reinforcing strip thus form shoulders arranged 55 to contact with the adjacent inclined walls of the corrugations of the conductor 10 so disposed as to prevent any rotary turning movement in either direction of the conductor within the support, this being a very

advantageous feature of my invention since 65 the support is thus not only adapted to hold the conductor as against vertical movement, but is also adapted to maintain the conductor perfectly rigid and stationary as against rotary turning movement. This 70 feature of construction is especially advantageous where the conductor 10 is formed in sections which are telescopically joined at their confronting ends since all movement of each of the sections is prevented, such as 75 would affect the permanency or the efficiency of the joints between the sections.

It will therefore be seen that we provide a very simple and efficient construction for the purpose set forth which may be readily 80 applied in use and while the device is particularly efficient when used in connection with a conductor, the wall of which is corrugated, still, the construction which we employ will be found very efficient, when used in connection with conductors, the walls of which are smooth or circular, since the body portion of the reinforcing strip will provide a shoulder upon the inner face of the body portion of the support, adapted to bear into 90 the smooth wall of the conductor. However, in this connection, attention is called to the fact that where a corrugated conductor is employed, one of the ridges of the corrugations may be disposed between the 95 confronting ends of the body portion 12 of the support, as shown in Fig. 3 of the drawings, so that when the locking member 19 is applied, the said extremities of the body portion will be brought together to engage 100 the oppositely inclined walls upon each side of said ridge to thus effectually grip the conductor and further prevent any rotary turning movement thereof.

Having thus described our invention, 105 what we claim and desire to secure by Letters Patent is:—

1. A device of the character described including a body portion adapted to embrace a conductor, a reinforcing strip carried by 110 the body portion and arranged to extend transversely of the inner face thereof, said reinforcing strip being bent adjacent its extremities to embrace the side edges of the body portion with the ends thereof overlapping the outer face of the body portion, means for operatively supporting the body portion and extending therethrough and through the reinforcing strip, and means for detachably locking the body portion 115 upon the conductor.

2. A device of the character described including a body portion, said body portion being substantially in the form of a split ring and having laterally extending outwardly turned flanges formed thereon adjacent its extremities, said flanges converging 125 toward one side edge of the body portion,

a reinforcing strip carried by the body portion and disposed to extend transversely of the inner face thereof, means for operatively supporting the body portion and extending 5 therethrough and through said reinforcing strip, and a locking member for securing the extremities of said ring together, said locking member having oppositely disposed flanges formed thereon, said flanges con- 10 verging toward one side edge of the locking

member and being adapted to engage the flanges of the ring.

In testimony whereof we affix our signatures in presence of two witnesses.
